UNITED STATES PATENT OFFICE.

SAMUEL J. RUSSELL, OF PRINCETON, TEXAS.

SUNSHADE.

Application filed November 24, 1922. Serial No. 603,038.

To all whom it may concern:

Be it known that I, SAMUEL J. RUSSELL, a citizen of the United States, residing at Princeton, in the county of Collin and State of Texas, have invented certain new and useful Improvements in Sunshades, of which the following is a specification.

This invention relates to head canopies or coverings supported from the person in position to protect the head from the sun, rain, snow and the like, while leaving the hands and arms free, and has for one of its objects to simplify and improve the construction and increase the efficiency and utility of devices of this character.

Another object of the invention is to provide a device of this character which is yieldably supported and automatically adaptable to the movements of the body. With these and other objects in view, the invention consists in certain novel features of construction as hereinafter shown and described and then specifically pointed out in the claims, and in the drawings illustrative of the preferred embodiment of the invention.

Figure 1 is a perspective view of the improved device arranged upon the figure of a man.

Figure 2 is a plan view without the fabric top.

Figure 3 is a front elevation with the fabric top in transverse section.

Figure 4 is an enlarged detail of the yieldable portion of one of the standards or "ribs."

The improved device includes two coacting belts 10 and 11 provided respectively with buckles 12 and 13 and adapted to be disposed around the person, indicated conventionally at 14, in spaced relation, and connected at suitable intervals by preferably flexible straps, indicated at 15.

Shoulder engaging straps 16 are attached to the upper belt 10 and each provided with an adjusting buckle 17.

The parts 10—11—15 and 16 constitute a harness like structure whereby the improved device may be supported upon and readily adjustable to the size of the person.

The canopy portion of the improved device comprises an endless band 18 preferably circular, and having a plurality of standards or rods 19, for instance four, attached at their upper ends at 20 to the band 18, and in uniformly spaced relation.

At its lower end each of the standards 19 is formed into a coil 21 with the lower terminal of each coil attached as shown at 22 to the belt 11. By this means the canopy top is yieldably supported in position both laterally and vertically, as will be obvious.

Attached to the upper belt 10 are a plurality of guides or keepers 23, one for each of the standards 19, as shown, by which means the standards and the band 18 carried thereby are supported from lateral displacement.

The band 18 forms a support for a fabric top or cover including a flat upper portion 24 and drop or depending portion 25, of any suitable texture.

The top or cover member 24—25 may be of water proof material such as light rubberized cloth, or the like, to render the device rain or snow proof, or of light cloth material for protection from the sun's rays, as may be preferred, the frame may be of any size or contour.

The parts 18, 19 and 21 will preferably be of metal as light as possible consistent of the strain to which they will be subjected, and the lower portions of the rods 19 may be covered with rubber tubing as indicated at 26 in Figure 4, to protect the person of the wearer from abrasion by the metal of the rods.

The preferred embodiment of the invention is disclosed in the drawings and set forth in the specification, but it will be understood that modifications within the scope of the claims may be made in the construction without departing from the principle of the invention or sacrificing any of its advantages.

Having thus described the invention what is claimed as new is:

1. A device of the class described including coacting upper and lower belts adapted to be supported in spaced relation around the person of the wearer, a plurality of springs attached to the lower belt, a standard extending from each of said springs, guides for said standards attached to said upper belt, flexible members coupling said belts, shoulder engaging members connected to said upper belt, and a canopy device supported by said standards.

2. A device of the class described including coacting upper and lower belts adapted to be supported in spaced relation around the person of the wearer, a canopy device,

and a plurality of standards connected at one end to said canopy device and each terminating in a coil connected respectively to said lower belt.

5 3. A device of the class described including coacting upper and lower belts adapted to be supported in spaced relation around the person of the wearer, a canopy device, a

plurality of standards connected at one end to said canopy device and each terminating in a coil connected respectively to said lower belt, and a guide keeper for each standard connected to said upper belt. ¹⁰

In testimony whereof, I affix my signature hereto.

SAMUEL J. RUSSELL.
